United States Patent Office

Des. 228,842
Patented Oct. 30, 1973

228,842

SOAP DISH HOLDER

Raymond U. H. Tegner, Rockford, Ill., assignor to
Amerock Corporation, Rockford, Ill.

Filed Jan. 10, 1972, Ser. No. 216,892

Term of patent 14 years

Int. Cl. D6—06

U.S. Cl. D6—89

FIG. 1.

FIG. 2.

FIG. 5.

FIG. 3.

FIG. 4.

FIG. 1 is a side view of the soap dish holder incorporating my new design.

FIG. 2 is a top view of the soap dish holder.

FIG. 3 is an end view.

FIG. 4 is a sectional view taken along the line 4—4 in FIG. 2.

FIG. 5 is a sectional view taken along the line 5—5 in FIG. 2.

FIG. 6 is a sectional view taken along the line 6—6 in FIG. 2.

The portion shown in broken lines forms no part of the design.

I claim:

The ornamental design for a soap dish holder, as shown and described.
